UNITED STATES PATENT OFFICE.

JAMES M. YOUNG AND JOHN B. GEYSER, OF ALLEGHENY, PENNSYLVANIA;
SAID GEYSER ASSIGNOR TO SAID YOUNG.

BALL-COCK.

SPECIFICATION forming part of Letters Patent No. 506,145, dated October 3, 1893.

Application filed December 17, 1892. Serial No. 455,429. (No model.)

To all whom it may concern:

Be it known that we, JAMES M. YOUNG and JOHN B. GEYSER, citizens of the United States, residing at Allegheny, in the county of Allegheny and State of Pennsylvania, have invented certain new and useful Improvements in Ball-Cocks or Water-Valves; and we do hereby declare the following to be a full, clear, and exact description of the invention, such as will enable others skilled in the art to which it appertains to make and use the same.

Our invention has relation to certain improvements in ball cocks, or water valves for closet cisterns and tanks, and particularly to that class of valves in which the opening of a small vent in the upper part of the valve-casing or cap causes the initial pressure in the supply connection to raise the main valve and allow the water to flow into the cistern or tank under full head; and in which, when the small vent is closed by the raising of the float, or other means, the pressure upon the upper part of the main valve will close the same gradually.

Our invention and improvements consist in the novel construction and combination of parts hereinafter described and claimed.

In the accompanying drawings,—Figure 1 is a vertical central sectional view of our improved ball-cock, with the valve seated. Fig. 2 is a similar view with the valve lifted. Fig. 3 is a transverse sectional view on the line $x-x$ of Fig. 1. Fig. 4 is a detailed view.

A is the supply-stem or inlet provided with suitable nut P and union joint P to secure to tank. The passage of A is unobstructed and larger in size than the service inlet at the union joint, but is provided at the top with a valve-seat B, and flange S, on the outer edge of which it is joined by screw-thread to the casing C. Inside this casing, which is larger in diameter than the supply opening, is located the automatic opening and closing valve E, which moves freely in the finished walls of C, being of sufficient length to afford a wide bearing against the wall of the casing, whereby it is self guiding and incapable of binding and has its upper edge packed by the leather disk F', secured to the valve E by the screw-ring F, the top edge, U, of which is dished to allow the water to reach the full diameter, when

the operation of closing begins. In the bottom center of valve E is screwed the pressure-tube L, retaining the leather valve L', which matches the seat B, in place, by the shoulder R. This pressure-tube extends, for some distance, down into A, and even when the valve E is open, is below the orifice of seat B. This tube is unsupported by bridge or guide, being centered and guided solely by the piston valve and hence its presence does not obstruct the passage way of the water through the inlet pipe A. The area or diameter of the pipe A, is sufficiently large to compensate for the space occupied by the pressure tube. The tube L ends in a conical point. The main portion of the tube L has a large bore M, to within a short distance of the conical point, where it is reduced to a very small sized passage N. The casing C has a closing cap G, screwed on its upper edge. This cap is provided with the exit passage H, ending in the vent I. Closing this vent, is the leather K, seated in the lever J, pivoted to the cap, and controlled by a float or other means. The casing C has also the side ports D, D, D, for the water to pass into the tank, and the flange T, to prevent it from boiling upward. The vent I throws water downward.

The operation of the valve is as follows: The area of the vent I is somewhat larger, in proportion to the inlet of the pressure-tube N, than the area of the large valve-chamber of C is to the supply-valve; in other words, if the area of C be five times the area of B, then the vent I should be at least six times the area of the entrance to the pressure-tube L, at N. This is vital, as it governs the automatic action of the valve. It is also a vital point to have the end of the pressure-tube L extend below the level of the valve seat B into the supply-stem A, so that the full pressure of the mains shall be steadily entering at N. Supposing now, that the valve is in working order and closed. Either by the fall of water lowering the float, or by other means, the vent I is opened and discharging more fluid than enters the chamber of C by the opening N. The pressure in A, on leather valve L', causes the valve E to slowly rise and the full volume of the supply rushes from A through B and out of the side openings D,

D, D in C, being prevented from jumping upward by the flange T, on C. The flow through N and out of I is also continuous so long as I remains open. When, however, the tank fills 5 and the vent I is closed by the float operating the lever J, or by other means, the supply through the pressure-tube L, by the small opening N, continues, and, owing to the opening being below the level of the seat B, the pressure tube conveys the full pressure of the 10 mains into the large chamber of C, and this being so much larger in area than the inlet of A, the force accumulated therein is sufficient to overcome all friction and resistance, 15 and firmly close the supply at B.

The object of the conical point on the pressure-tube L is to allow a free passage for any foulness that may be in the fluid, and the enlarged passage M above N is to avoid the possibility of its fouling with small particles. 20 This valve being submerged is noiseless, and the action perfect, the extension of the pressure-tube L below the seat of B at all positions, open or closed, allowing the full power of the water pressure to be used for work, and the 25 simple proportioning of the vent I so as to discharge more than the inlet N can supply, furnishing the movement. It will work in any position in which it may be placed, and 30 under any grade of pressure that is sufficient to overcome the slight friction of the parts. Although we have here shown it as applied to tank use, its adaptability to many other uses is apparent.

35 We are aware that other valves and cocks have been made, having the object of using

the pressure of supply to control and close the valve, but owing to the complexity and delicacy of their parts, they have proven practical failures, not being able to meet the requirements of varying pressure and foulwater. 40

Having described our invention, what we claim, and desire to secure by Letters Patent, is—

1. In a ball cock or water valve, the combination with the unobstructed inlet stem A, of the valve casing C, having outlet openings of greater aggregate area than the stem A, the plunger E, sliding freely within the casing and having its external bearing surface sufficiently large to prevent binding and the pressure tube L, attached to the plunger and extending into the stem A, when the plunger is both raised and lowered, said pressure tube being centered and guided solely by the piston 50 valve, and having its upper end threaded and shouldered, and retaining in place the valve L', substantially as described. 55

2. In a ball cock or water valve, the combination with the hollow cylindrical piston or 60 plunger having a central water way and having at its upper end an internal flange threaded interiorly and recessed on its upper face, of the flexible packing disk F', and flanged screw ring F, substantially as described. 65

In testimony whereof we affix our signatures in presence of two witnesses.

JAMES M. YOUNG.
JOHN B. GEYSER.
